Inventor,

Alfred H. Humphrey
By Red L. Cappell
Att'y.

UNITED STATES PATENT OFFICE.

ALFRED H. HUMPHREY, OF KALAMAZOO, MICHIGAN.

BUNSEN BURNER.

SPECIFICATION forming part of Letters Patent No. 742,990, dated November 3, 1903.

Application filed January 10, 1903. Serial No. 138,489. (No model.)

To all whom it may concern:

Be it known that I, ALFRED H. HUMPHREY, a citizen of the United States, residing at the city of Kalamazoo, in the county of Kalamazoo and State of Michigan, have invented certain new and useful Improvements in Bunsen Burners, of which the following is a specification.

This invention relates to improvements in Bunsen burners, and particularly to improvements in a needle gas-supply valve for a Bunsen burner.

The objects of the invention are, first, to provide an improved construction of needle-valve in which the needle-point is so evenly supported and adjusted that there is an even delivery of the jet of gas around the point; second, to provide an improved ready means for supporting and guiding the needle of such a needle-valve; third, to provide an improved means of adjusting the needle of such a needle-valve.

Further objects relating to details of construction will definitely appear in the detailed description to follow.

I accomplish the objects of my invention by the devices and means described in the following specification.

The invention is clearly defined, and pointed out in the claims.

A structure embodying the features of my invention is fully illustrated in the accompanying drawings, forming a part of this specification, in which—

Figure 1 is a detail sectional view of my improved needle-valve for Bunsen burners, taken on a line corresponding to the irregular line 1 1 of Fig. 3. Fig. 2 is a vertical detail sectional view on line 2 2 of Fig. 1, showing the rack on the side of the needle and the pinion by which it is actuated. Fig. 3 is a horizontal sectional view taken on line 3 3 of Fig. 1, showing the perforated diaphragm which supports and guides the needle in position and the relation of the adjusting means.

In the drawings similar letters of reference refer to similar parts throughout the several views and the sectional views are taken looking in the direction of the little arrows at the ends of the section-lines.

Referring to the lettered parts of the drawings, the gas-pipe A is provided with a burner-

base B, screwed thereon in the usual way, and this terminates in the needle-valve seat at its upper end. The needle D is preferably supported in the central position by diaphragms or horizontal partitions e, which are suitably perforated for the free passage of the gas to the needle-valve above. The needle D is in a central aperture in these diaphragms e. These diaphragms are supported in position by friction, they being crowded closely into the burner-base B. On one side of the needle D is formed a rack D'. A transverse sleeve E" is inserted into the side of the burner-base B, making an opening into the same between the diaphragms e e. A thumb-screw E is screw-threaded into this sleeve, and the inner end of this thumb-screw E is formed into an elongated small pinion E', which meshes with the rack D' of the needle D. The point of the needle fits into a usual valve-seat provided for needle-valves. The threads of the thumb-screw E fit snugly and make a gas-tight connection, and as the pinion engages the rack the needle is prevented from rotation and is moved up and down very speedily by the manipulation of the thumb-screw, so that to turn up or to turn down the gas requires the same manipulation as in an ordinary kerosene-lamp. It is very important to be able to readily adjust the flow of gas in a Bunsen burner, particularly where incandescent mantles are used, as it needs a speedy regulation of the burner to secure the greatest efficiency for the gas consumed by regulating exactly the mixture of the gas with the air in the burner so as to secure the very best proportions. This device is used with the improved burner-tube C, which is slightly tapered upwardly with an abrupt expansion at the top, though it is well adapted for use with any kind of mixing-tube that may be used with a Bunsen burner.

While I have shown my improved needle-valve for Bunsen burners illustrated in the exact form in which I am now manufacturing it, which I consider possesses merit over any other owing to the superior guiding of the needle and its speedy adjustment, I am aware that the details of the structure can be greatly varied without departing from my invention. I, however, desire to claim the

specific details as well as the broad features of the invention. The valve structure itself is adapted to other uses than in connection with Bunsen burners, and I desire to claim that structure broadly. It is obviously the main invention here presented and is also desired to be claimed in connection with the parts which make up a complete Bunsen burner.

Having thus described my invention, what I claim as new, and desire to secure by Letters Patent, is—

1. In a valve structure for Bunsen burners, the combination of the gas-supply pipe A; the burner-base B suitably secured thereto, and terminating in a needle-valve seat at its upper end; perforated diaphragms e e within the same; a needle D supported in suitable guiding-perforations in the diaphragms or partitions e e, and provided with a rack D' upon one side; a laterally-arranged internally-screw-threaded tube or sleeve E' opening into the burner-base between the diaphragms e; a thumb-screw E extending through the same, terminating at its inner end, in an elongated pinion E' meshing with the rack D' on the needle D; a suitable mixing-tube above the needle-valve, for the purpose specified.

2. In a valve structure for Bunsen burners, the combination of the gas-supply pipe A; the burner-base B suitably secured thereto, and terminating in a needle-valve at its upper end; perforated diaphragms e e within the same; a needle D supported in suitable guiding-perforations in the diaphragms or partitions e e, and provided with a rack D' upon one side; a laterally-arranged internally-screw-threaded tube or sleeve E' opening into the burner-base between the diaphragms e; a thumb-screw E extending through the same, terminating at its inner end, in an elongated pinion E' meshing with

the rack D' on the needle D, for the purpose specified.

3. In a valve structure for Bunsen burners, the combination of the burner-base B terminating in a needle-valve seat at its upper end; perforated diaphragms e e within the same; a needle D supported in suitable guiding-perforations in the diaphragms or partitions e e, and provided with a rack D' upon one side; a laterally-arranged internally-screw-threaded tube or sleeve E' opening into the burner-base between the diaphragms e; a thumb-screw E extending through the same, terminating at its inner end, in an elongated pinion E' meshing with the rack D' on the needle D, for the purpose specified.

4. In a valve structure for Bunsen burners, the combination of the burner-base having a gas-passage terminating in a needle-valve seat at its upper end; a needle D suitably guided within the burner-base, and having a rack D' formed in the side of the needle; a thumb-screw E having its inner end formed into a pinion adapted to mesh with said rack D', and screw-threaded through the side of said base, for the purpose specified.

5. In a valve structure for a Bunsen burner, the combination of a burner-base B terminating in a needle-valve seat at its upper end, perforated diaphragms e e within the same; a needle D supported in suitable guiding-perforations in the diaphragms or partitions e e and provided with a rack D' upon one side; a pinion engaging said rack between said diaphragms; and an operating-shaft for said pinion, for the purpose specified.

In witness whereof I have hereunto set my hand and seal in the presence of two witnesses.

ALFRED H. HUMPHREY. [L.S.]
